UNITED STATES PATENT OFFICE

107,796

DESIGN FOR A FACE POWDER BOX

Elsa Schiaparelli, Paris, France

Application November 17, 1937, Serial No. 72,951

Term of patent 14 years

To all whom it may concern:

Be it known that I, Elsa Schiaparelli, a citizen of the Republic of France, residing in the city of Paris and Republic of France, have invented a new, original, and ornamental Design for a Face Powder Box, of which the following is a specification, reference being had to the accompanying drawing, forming a part thereof.

In the drawing:—

Fig. 1 is a top view of a face powder box showing my design.

Fig. 2 is a front view thereof.

I claim:—

The ornamental design for a face powder box, as shown.

ELSA SCHIAPARELLI.
